US0D1079441S

(12) **United States Design Patent** (10) **Patent No.:** **US D1,079,441 S**
(45) **Date of Patent:** **** Jun. 17, 2025**

(54) **ADAPTOR**

(71) Applicant: **Bang & Olufsen A/S**, Struer (DK)

(72) Inventor: **Torsten Valeur**, Copenhagen V (DK)

(73) Assignee: **Bang & Olufsen A/S**, Struer (DK)

(**) Term: **15 Years**

(21) Appl. No.: **29/798,800**

(22) Filed: **Jul. 9, 2021**

(30) **Foreign Application Priority Data**

Jan. 20, 2021 (EM) 008408298-0006

(51) **LOC (15) Cl.** **13-02**

(52) **U.S. Cl.**

USPC **D13/108**

(58) **Field of Classification Search**

USPC D8/354; D13/107, 108; D14/214, 223,
D14/224, 240, 358, 433, 496

CPC F16M 13/02; F16M 11/041; H02J 7/0042;
H04R 1/02; H04R 2400/11; H04R 7/04

See application file for complete search history.

(57) **CLAIM**

The ornamental design for an adaptor, as shown and described.

DESCRIPTION

FIG. 1 is a front perspective view of an adaptor;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the adaptor that form no part of the claimed design.

1 Claim, 8 Drawing Sheets
